(No Model.)

P. J. MAGUIRE.
CARBONIC ACID GAS GENERATOR.

No. 478,198.

Patented July 5, 1892.

UNITED STATES PATENT OFFICE.

PATRICK J. MAGUIRE, OF SALEM, ASSIGNOR TO THE AMERICAN SODA FOUNTAIN COMPANY, OF BOSTON, MASSACHUSETTS.

CARBONIC-ACID-GAS GENERATOR.

SPECIFICATION forming part of Letters Patent No. 478,198, dated July 5, 1892.

Application filed March 29, 1892. Serial No. 426,961. (No model.)

To all whom it may concern:

Be it known that I, PATRICK J. MAGUIRE, a citizen of the United States, residing at Salem, in the county of Essex and State of Massachusetts, have invented certain Improvements in Carbonic-Acid-Gas Generators, of which the following is a full, clear, and exact description, reference being had to the accompanying drawings, making part of this specification, in which—

Figure 1 is a transverse vertical section of a carbonic-acid-gas generator embodying my invention. Fig. 2 is a top view of the acid-chamber. Fig. 3 is a horizontal section on the line $x-x$ of Fig. 1.

My invention relates to an improvement on the carbonic-acid-gas generator for which Letters Patent of the United States No. 467,673 were granted to me January 26, 1892, and has for its object to improve the construction of the apparatus whereby explosion from excessive pressure is rendered impossible under any circumstances whatever; and to this end my invention consists in the combination, with the back-pressure or check valve which is applied at the upper end of the siphon rising within said acid-chamber and communicating with the alkali-chamber, of an adjustable pressure-regulating governor connected with said check-valve in such manner that while it will not interfere with the ordinary operation of the latter it will, when the pressure in the acid-chamber reaches a predetermined point, open said check-valve to equalize the pressure in the acid and alkali chambers and hold said valve open so long as the pressure remains at or above the point at which said governor has been set to act, thus stopping all further flow of acid, holding the pressure in the apparatus at the proper working-point, whether it is in operation or not, and preventing any undue accumulation of acid in the alkali-chamber when the agitators are at rest, as hereinafter more particularly set forth.

In the said drawings, A represents the alkali-chamber of a carbonic-acid-gas generator, upon which is secured, by means of bolts a , in the ordinary manner, the acid chamber or receptacle B, provided, as usual, with a lead

lining b , the passage between the said chambers A, B being provided with a lead bushing c , having a flange d , which is confined between the flanges of the acid and alkali chambers, as shown, a suitable packing of lead being provided at the joint between the said chambers, as usual. Within the upper end of the bushing c is fitted the end of a pipe D, which extends up vertically within the acid-chamber B, and is surrounded by an outer 60 casing or jacket E, the lower end of which is tightly soldered to the upper surface of the flange d of the bushing c , immediately above which and as closely as possible to the bottom of the acid-chamber are formed openings 65 f for the passage of the acid which flows into the space 10 between the jacket E and the pipe D and rises within said space until it finds its level. The upper end of the jacket E, which extends above the top of the pipe 70 D, is provided with a back-pressure or check valve G, opening upward into the acid-chamber, through which valve the gas from the alkali-chamber may escape into the acid-chamber B to create a pressure upon the 75 surface of the acid therein, the pipe D and outer casing E when the valve G is closed forming a siphon through which the acid is delivered to the alkali-chamber A, and thus whenever the pressure in the chamber B exceeds that in the alkali or generating chamber A the acid is caused to flow over the top of the pipe D and down therethrough into the alkali-chamber A, while as soon as the pressure in the generating-chamber A equals that 80 in the chamber B the flow of acid will be stopped, and consequently the generation of gas will be checked and liability of explosion avoided, the pipe D thus forming a portion of the equalizing-pipe, and also serving as a 85 delivery-pipe for the acid.

k is an opening in the cover g , through which the acid is poured into the chamber B, said opening being closed by a screw-cap l . (Shown dotted in Fig. 2.)

H is a pressure-gage, and I a safety-valve, both of the usual construction.

The apparatus thus far described is substantially the same as that shown and described in my aforesaid Letters Patent of 100

January 26, 1892, its construction and mode of operation being referred to in order to more clearly illustrate the improvements which form the subject of my present invention, and which I will now proceed to describe.

The cover *g* of the acid-chamber *B* is provided at its center with a large aperture having a threaded bushing *h*, to which is fitted a pressure-regulating governor *K*, provided between the upper and lower portions of its casting with an elastic diaphragm *m*, to the upper side of which is fitted a vertical spindle *n*, which projects up through a cylindrical chamber *p* at the top of the governor-casing, within which said spindle is encircled by a spiral spring *q*, confined between a washer *15*, resting on the shoulder *16* of the governor-casing, and an adjustable cap *r*, screwed over the top of the chamber *p*, the force of the spring *q* being regulated by screwing the cap *r* up or down, whereby the governor may be adjusted or set so that its diaphragm will be raised when a predetermined gas-pressure in the acid-chamber is reached, this pressure being preferably that at which the apparatus is to be worked. The spindle *n* extends up through an aperture *s* in the screw-cap *r* and is provided at its top with a knob or enlargement *t*, the movement of which will indicate when the governor has been properly adjusted to act at a given pressure, as indicated by the pressure-gage *H*. To the under side of the diaphragm *m* is secured a spindle *w*, which passes through a guide *a'*, and is provided at its lower end with a cylindrical coupling *L*, which is loosely connected with the stem *b'* of the back-pressure or check valve *G* in such manner as not to interfere with the ordinary operation of the latter, previously described, the stem *b'* sliding freely through the bottom of the coupling *L* and being provided at its upper end with a nut *c'*, with which the bottom of the coupling *L* is brought into contact when the pressure of gas in the chamber *B* is sufficient to overcome the pressure of the spring *q* and raise the diaphragm *m*, the valve *G* being thus opened and held open as long as the working or other pressure at which the governor has been set to act is maintained, thus preventing any further flow of the acid into the chamber *A* and holding the pressure in the apparatus at the proper working point whether it is in operation or not, whereby all danger of explosion under any circumstances whatever is avoided.

It will be obvious that the holding of the check-valve *G* open by means of the governor *K* whenever the gas-pressure in the apparatus reaches a predetermined limit will effectually prevent any accumulation of acid in the alkali-chamber *A* in case the apparatus should be left by the attendant with the agitator-blades at rest, for the reason that if, in consequence of a slight leakage of gas at the joints, the pressure should become reduced in the chamber *A* and a consequent flow of

acid from the chamber *B* should be produced, causing an increase of pressure above the desired limit, no further or subsequent flow of acid could take place on account of the check-valve *G* being held open, as above described, and therefore when the agitator-blades are again set in motion there will be no excessive quantity of acid in the chamber *A*, thus avoiding all liability of explosion from a sudden evolution of a volume of gas too great to be relieved by the safety-valve *I*.

In starting the apparatus, the chamber *B* having been filled with acid to the level of the top of the delivery-pipe *D*, a small additional quantity of acid is poured in through the opening *k*, which is then immediately closed by screwing the cap *l* tightly down thereover. This raises the level of the acid above the top of the pipe *D*, causing it to flow simply by gravitation down through said pipe *D* into the alkali-chamber *A*, containing the usual supply of marble-dust and water. The gas generated in the chamber *A* then rises into the pipe *D*, and when the pressure in the chamber *A* rises to a sufficient height it will force the column of liquid in the pipe *D* bodily upward and into the chamber *B*, compressing the gas therein until such pressure, plus the column of liquid in the pipe *D*, is equal to the gas-pressure in the chamber *A*. The flow of acid will then cease until the pressure in the chamber *A* is lowered. The gas in the chamber *B* will then expand, and, being prevented by the valve *G* from passing through the pipe *D*, will force the liquid through said pipe, when the flow of the acid will be resumed. The action is thus automatic and regulated by the generation of gas in the chamber *A* and the rapidity with which such gas is used, no care or attention on the part of the attendant being necessary so long as the acid-chamber contains a supply of acid, the operation of the apparatus being thus regulated with the greatest nicety. After the apparatus has been started the governor *K* is set by screwing down the cap *r*, and thereby compressing the spring *q* sufficiently to counterbalance the working pressure desired in the generator, as indicated by the pressure-gage *H*, after which, when from any cause the pressure in the chamber *B* rises above the desired limit, the valve *G* will be raised by the action of the governor *K* and held open until the pressure is reduced below the fixed limit, as previously described.

The acid-chamber is provided at its bottom with an opening *d'* to facilitate the operation of washing out said chamber, the opening being closed by a screw-cap *e'*, and the alkali-chamber is also provided with a suitable outlet-pipe *f'*, controlled by a valve *g'*, through which the contents may be drawn out when desired.

What I claim as my invention, and desire to secure by Letters Patent, is—

1. In a carbonic-acid-gas generator, the combination, with the acid-chamber having with-

- in it a siphon communicating with the alkali-chamber and provided with a back-pressure or check valve, substantially as described, of a pressure-regulating governor connected 5 with said check-valve and adapted to hold the latter open whenever the pressure in the acid-chamber rises to or above a point at which said governor has been set to act, substantially as set forth.
- 10 2. In a carbonic-acid-gas generator, the combination of an acid-chamber, a siphon placed within said chamber and communicating with the alkali-chamber, said siphon being provided with a back-pressure or check valve, 15 which when open will equalize the pressure in the acid and alkali chambers and prevent the flow of the acid, and an adjustable pressure-regulating governor having a spring and diaphragm, the latter connected with said 20 check-valve in such manner as to permit the latter to operate independently of the governor, said governor being adapted to hold the check-valve open whenever the pressure in the acid-chamber is at or above the desired 25 limit, substantially as set forth.
3. In a carbonic-acid-gas generator, the combination, with the acid-chamber, of a vertical pipe rising within said acid-chamber and communicating with the alkali-chamber, an outer 30 casing or jacket surrounding said vertical pipe and provided at its bottom with an inlet for the passage of the acid to the space between said vertical pipe and its outer casing or jacket, a back-pressure or check valve applied to the upper end of the jacket above the 35 end of the vertical pipe inclosed thereby and

opening into the acid-chamber, and an adjustable pressure-regulating governor loosely connected with the check-valve and adapted to open the same and hold it open whenever the pressure in the acid-chamber rises to or above a point at which said governor has been set to act, substantially as set forth.

4. In a carbonic-acid-gas generator, the combination of the alkali-chamber A, the acid-chamber B, provided with a pressure-gage H, the vertical pipe D, rising within said acid-chamber and communicating with the alkali-chamber, the outer casing or jacket E, surrounding the pipe D and provided at its bottom with an inlet for the passage of the acid to the space between the pipe D and its jacket E, the back-pressure or check valve G at the upper end of the jacket E, said valve opening into the acid-chamber, the adjustable pressure-regulating governor K, having the spring q, screw-cap r, and diaphragm m, the latter connected by means of the coupling L with the stem b' of the valve G in such manner as to permit said valve to operate independently of the governor, said governor being adapted to hold the valve G open whenever the pressure in the acid-chamber is at or above the desired limit, all operating substantially in the manner and for the purpose described.

Witness my hand this 23d day of March, A. D. 1892.

PATRICK J. MAGUIRE.

In presence of—

P. E. TESCHEMACHER,
J. F. HINDS.
